UNITED STATES PATENT OFFICE.

ROBERT K. JACK, OF LANSING, MICHIGAN, ASSIGNOR TO GENERAL MOTORS CORPORATION, OF DETROIT, MICHIGAN, A CORPORATION OF DELAWARE.

ADJUSTABLE HOOD HINGE AND BRACE ROD.

Application filed December 6, 1924. Serial No. 754,360.

My invention relates to hood structures for enclosing the engines of motor driven vehicles; and the object thereof is to provide an improved adjustable hinge and brace rod device for connecting the upper ends of the radiator and cowl at the front end of the body of the vehicle together, which rod and the parts and features associated therewith in addition serve to provide a pivotal or hinge support for the upper ends of the doors commonly present in vehicle hoods.

The drawing accompanying and forming a part of this specification illustrates what I now regard as the best form of my invention; although the same may be variously modified, and is regarded as including all such variations and modifications of the particular form shown as come within the scope of the concluding claims, wherein the distinguishing features in which my invention consists are particularly pointed out.

In the drawing:

Figure 1 is a fragmentary view, mostly in side elevation, showing the upper ends 25 of the radiator structure and the cowl of a motor driven vehicle connected together by a hood hinge and brace rod device made in accordance with my invention.

Figure 2 is a similar view showing the 30 parts in plan.

Figures 3 and 4 are side and plan views upon a larger scale than Figures 1 and 2 showing the hinge and brace rod element by itself, and apart from the radiator, the 35 cowl and the doors of the hood.

Referring to the drawing, the reference numeral 5 designates the cowl or front end of the body of a motor driven vehicle, and 6 the radiator structure whereby the water 40 employed for cooling the engine of the vehicle is cooled. The exterior casing only of the radiator is shown as the water cooling elements and features thereof form no part of this present invention, and may be 45 of any suitable form.

The ends of the cowl and radiator casing are suitably shaped to provide jamb or abutment portions 7 and 8 upon which the rear and front edges of the hood doors 9, 10 rest 50 when the doors are closed, at which time they provide a housing enclosing the engine which drives the vehicle as will be understood.

Extending between the upper ends of the 55 radiator and cowl is a combined brace and

hinge rod 11 which forms a pivot for the hinges 12 at the upper ends of the doors 9, 10 as is usual in hood door constructions. The two ends of said rod are connected, respectively, to the radiator structure and to 60 the cowl; and said rod as will be observed constitutes the only connection between the upper ends of said parts and serves as a brace and tie rod which maintains them the proper distance apart or, as otherwise expressed, 65 holds the radiator structure in its proper upright position as the cowl (being a part of the body) is the more immobile of the two members connected by the rod.

The front end of the rod 11 is bent down 70 at 13, and provided with a hole at 14 to receive a cottor pin; said hooked end being adapted to pass through a hole in the jamb or flange 8 of the radiator casing when the 75 rod is in use.

The rear end of the brace and hinge rod 11 is threaded at 15, and screws more or less into a threaded extension or neck 16 of a connecting member 17 whereby and through which the said rear end is fastened to the 80 cowl 5. Said connecting member is provided with a hole 18 at right angles to the neck 16, and the same is shown as fastened to the jamb portion 7 of the cowl by a bolt 19, the 85 nut of which is indicated by the numerical 20. A collar 21 is shown as arranged so that the hook 13 extends therethrough; and both the collar and the nut 20 are preferably fastened (as by welding) to the jambs 7 and 8, in order to secure large areas as the joints 90 between the ends of the rod and the cowl and radiator and prevent the sharp edges of the sheet metal from which said members are made from cutting the part 13 and the bolt 19. Obviously the position of the connecting member 17 and hook 13 may be reversed, 95 as it is immaterial which end of the rod is fastened to the radiator casing and which to the cowl.

In making use of my improved adjustable 100 connector and hinge rod device the hook shaped end 13 is connected with the flange or jamb 8 as hereinbefore explained, and the connecting member 17 screwed to a greater or less extent upon the threaded 105 end 15 of the rod 11; the doors being in place during such adjustment of the parts and the rear end of the rod being lifted slightly when the connecting member is to be screwed on or off the rod as will be 110

understood. By such a number of repeated trials as may be necessary a position of the connecting member may be found such that the radiator structure will be properly positioned relative to the fan and other parts of the engine not shown, and such that the front and rear ends of the doors will rest properly upon the jambs 7 and 8 with the hole 18 in alignment with the nut 20 and 10 with the hole in the jamb 7 through which the bolt 19 is to pass; whereupon the connecting member and rear end of the rod 11 are fastened to the cowl structure by putting the bolt 19 in place, as will be understood.

15 Having thus described and explained my invention I claim and desire to secure by Letters Patent:

1. An adjustable connector and hood door hinge device comprising in combination a rod bent to form a hook at one end thereof, and which rod is threaded at its other end; and a connecting member having an internally threaded neck adapted to receive the threaded end of said rod, and a hole extending at right angles to the axis of said rod and neck and adapted to receive a fastening bolt.

2. An adjustable connector and hood door hinge device for motor driven vehicles comprising in combination a hinge rod, and means at one end thereof for connecting said end to a radiator structure; a connecting member at the other end of said rod; means

for fastening said connecting member and the second mentioned end of said rod together in various positions; and means for fastening said connecting member to the front end of the body of a motor driven vehicle.

3. An adjustable connector and hood door hinge device of the class described comprising in combination a hinge rod, and means at one end thereof for connecting said end to a radiator casing; a connecting member at the other end of said rod and having a tubular neck into which said other end extends, and wherein it may be secured in various positions to thereby adjust the device; and a bolt cooperating with said connecting member and adapted to fasten the same to the front end of a vehicle body.

4. An adjustable connector and hood door hinge device for motor driven vehicles comprising in combination a hinge rod, and means at one end thereof for connecting said end to a radiator structure without permitting relative longitudinal movement; a connecting member at the other end of said rod; means for fastening said connecting member and the second mentioned end of said rod together in various positions; and means for fastening said connecting member to the front end of the body of a motor driven vehicle.

In testimony whereof I affix my signature.

ROBERT K. JACK.
